NUTCRACKER

Charles W. Bereth, San Jose, Calif.

Application June 20, 1949, Serial No. 3,420

Term of patent 7 years

(Cl. D44—1)

To all whom it may concern:

Be it known that I, Charles W. Bereth, a citizen of the United States, residing at San Jose, in the county of Santa Clara and State of California, have invented a new, original, and ornamental Design for a Nutcracker, of which the following is a specification, reference being had to the accompanying drawing, forming a part thereof.

In the drawing:

Fig. 1 is a perspective view of a nutcracker embodying my new design and as seen from the handle end thereof.

Fig. 2 is an end view of the same taken substantially from line 2—2 in Fig. 1.

Fig. 3 is a bottom view of the same as seen from below in Fig. 1.

I claim:

The ornamental design for a nutcracker, as shown.

CHARLES W. BERETH.
